ANGULAR TUNING INDICATOR FACEPLATE

Maurice D. Katz, 35 Broadway, Lawrence, N.Y. 11559

Filed May 18, 1971, Ser. No. 144,701

Term of patent 14 years

Int. Cl. D14—03, 99

U.S. Cl. D26—1

FIG.1

FIG.2

FIG.3

FIG. 1 is a top plan view of an angular tuning indicator faceplate, embodying the features of my new design.

FIG. 2 is a perspective view of the angular tuning indicator faceplate.

FIG. 3 is a front perspective view.

The broken lines representing the radio is shown for illustrative purposes only.

I claim:

The ornamental design for an angular tuning indicator faceplate, substantially as shown and described.
